UNITED STATES PATENT OFFICE

WALTER C. WOOD, OF EDGEWOOD, RHODE ISLAND

MEANS FOR DETACHABLY CONNECTING SAILS TO SPARS

Application filed January 6, 1930. Serial No. 418,693.

This invention relates to improved means for detachably connecting sails to spars or the like; and has for its object to provide a cooperating removable section of track on the spars into which a set of the slides on the sail may be assembled when the sail is furled, which section when removed with the sail serves to retain these slides in their proper assembled relation so that when the sail is again being bent these track sections are readily repositioned on the spars and the slides conducted therefrom onto the fixed sections of the track.

The invention further consists in constructing the removable section of the rail to perform the function of a magazine and in a trough shape of a length to receive a full set of the sail slides, and to provide stop means in the magazine to prevent accidental removal of the sail slides stored therein, while the magazine and the sail are removed from the spars.

The invention further consists in the provision of means whereby the positioning of the magazine section at the end of the main track, automatically withdraws the retaining stop therein permitting the sail slides to be freely conducted therefrom onto the main track section.

With these and other objects in view, the invention consists of certain novel features of construction, as will be more fully described, and particularly pointed out in the appended claims.

In the accompanying drawings:

Fig. 1 is a view representing a boat with the sails in stretched condition.

Fig. 2 is an enlarged view showing the sail in partially stretched condition with the magazine track sections at the inner ends of the main track sections.

Fig. 3 shows the sail in furled condition with its slides stored in the magazine sections of the track.

Fig. 4 is an enlarged view of the magazine section of the track as mounted in its end guiding and retaining members with its stop pin at one end withdrawn.

Fig. 5 shows the magazine section of the track partly withdrawn with its lower end

swung to one side of its retaining member and its upper end nearly removed from its retaining member, and its stop pin as having sprung back into position to retain the slides therein.

Fig. 6 shows the magazine section of the track as completely removed and filled with the sail slide members, the stop pins at either end of this magazine being positioned to retain these sail slides in proper assembled relation.

Fig. 7 is a perspective view showing a short length of the trough-shaped magazine portion broken away to expose the stop pin in operative position therein.

Fig. 8 is a perspective view showing a short section of the substantially T-shaped guide rail on which the sail slides run.

Fig. 9 is a perspective view showing the retaining member for the outer end of the magazine section, and illustrating the cam on one side thereof for automatically withdrawing the stop pin of the magazine as the same is positioned.

Fig. 10 is a perspective view showing the lock member for receiving and retaining the inner end of the magazine section.

Fig. 11 is a section on line 11-11 of Fig. 6, showing the stop pin or member at the inner end of the magazine section.

Fig. 12 shows the removable stop pin at the outer end of the magazine section.

Fig. 13 is a perspective view of one of the sail slides which may run on the slide rail and also run into and be stored in the magazine section.

It is found in practice that where sails are furled on their spars, exposure to heat and moisture often causes them to mildew and so weaken the sails and injure their appearance, and therefore it has become the practice, particularly on small racing yachts having expensive sails, to remove the same from the spars after each day's use to permit of better care and afford greater protection; and in order to facilitate the ready removal of the sails from the spars, I have provided a detachable rail section at the end of the fixed rail section on the spars and onto or into this removable section the sail slides may run,

so that as the sails are lowered the set of slides on the hoist will be conducted automatically into their removable section, and those on the foot may be slid inward along the boom into their section. Provisions are made on each removable section for locking its slides therein when the sections are being removed with the sails from the spars, whereby these slides are caused to remain in their exact assembled relation or order so that when it is desired to again bend the sail, it is only necessary to reset these removable rail sections in their proper position on their respective spars and the slides are accurately guided to again run onto their fixed rail sections in proper order without the possibility of a single slide being left off or misplaced on its rail. Also by the use of my improved device, should occasion require, the particular size of sail being used, may be quickly changed for one of smaller size instead of reefing, if desired; and the following is a detailed description of the present embodiment of my invention and showing one means by which these advantageous results may be accomplished:

With reference to the drawings, 10 designates the mast and 11 the boom on the boat 12 on each of which is secured a main rail section 13 to extend substantially the length thereof. This rail is usually in somewhat of a T-form, as best illustrated in Fig. 8, and is secured to the spars by means of screws 14, the heads of which are set in the channel 15 along the center of its rail.

In order to provide simple and effective means for securing the sail to the spars, slide members 16 of the shape best illustrated in Fig. 13, are attached in spaced relation along the edges of the sail both along the hoist to run on the mast rail and along the foot to run on the boom rail.

In order to detach these slides from their respective rails, it has heretofore been the custom to leave the inner end of the rails free and run the slides off of this end and when it was desired to again bend the sail these slides were laboriously threaded onto the ends of their respective rails and often times one side of one would not be threaded and in some instances they would not be threaded in their proper order onto their rails, in which case if it happened to be one of the first of the series that was omitted the whole would have to be removed and the operation repeated to the great annoyance of the user.

To obviate this serious difficulty, I have provided a removable rail section for the inner end portion of each of the main fixed rail sections, onto or into which removable sections the slides may be readily run and then these sections removed from the spars along with the sail. These removable sections may be made in any suitable form but

I preferably make them trough shaped and each of a size to receive and retain a set of the sail slides. In order to facilitate the removal of these magazine sections, I have provided an outer retaining socket member 17 which comprises a base plate 18 arranged to be secured to the spar by screws 17^a at the inner end of the main rail section. This retaining socket has side walls 19 with overhanging flanges 20, the entering end between these side walls being flaring as at 21 to better receive and guide the outer end 22 of the magazine section thereinto. One wall at the entering end of this retaining socket is provided with a cam-shaped protuberance 23 for the purpose presently described. Also, I have provided a socket 24 for receiving and retaining the inner end of the magazine, the same having a base plate 25 adapted to be permanently secured by screws 25^a to the spar. This magazine end retaining socket is provided with a lock cam 26 housed in the box-shaped portion 27, the cam being pivoted at 28 therein and provided with an extending operating handle 29 pressed onto operative position by a compression spring 30.

The trough-shaped magazine sections 31 are each of a length sufficient to receive all of a set of sail slides 16 and has at its inner end a stop pin 32 which extends through its opposite side walls but any other form of stop may be employed. This magazine is also provided with a withdrawable stop pin 33 adjacent its opposite or outer end, which pin is mounted on a spring plate 34 attached at 100 one end by screws 35 to the side of the magazine, the opposite end 36 of the plate being turned outwardly to ride over the cam 23 when this magazine is pushed up into position in its outer socket as illustrated in Fig. 4, for the purpose of withdrawing the stop pin 33 to permit the sail slides 16 to be run from the magazine out onto their guide rail. When the inner end of this magazine section has been pushed into its outer retaining socket a sufficient distance, its inner end is swung inwardly into its socket 24 causing the cam 26 to compress its spring 30 and slide thereover and when carried back against the wall 37 this cam will spring back into the position illustrated in Fig. 4 to lock and retain the inner end of this magazine firmly in position.

By the use of my improved detachable rail sections, when it is desired to remove the sail from its spars, it is only necessary to lower the sail which causes the guides on the hoist to slide into its magazine section and to release the boom haul out, and run the slides along the boom track into its magazine section; then each of these two removable sections, by operating the cam lever 29, may be readily released and removed from its respective socket, the removing action of the magazine automatically releasing the stop pin 30 causing it to snap inwardly to prevent

inadvertent withdrawing of the slides from their respective magazines. The sail with its assembled slides may now be deposited into the bag, carried ashore and hung in a dry place, and when it is desired to air the sail it is only necessary to suspend the same, the folds being sufficiently loose, so that when exposed to the air and sun all portions are readily dried and when it is desired to again bend the sail it is only necessary to take it aboard the boat and snap the two magazines into their respective sockets, which automatically unlocks or removes the outer retaining members permitting the slides to be freely run out onto the rails of their respective spars without any possibility of their getting out of their proper order or getting free from their rails.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A device for detachably connecting sails to spars or the like, comprising a set of attaching members secured to the sail in spaced relation, means on the spars for controlling the path of travel of said members as the sail is being stretched and furled, and removable means positioned in the path of travel of said members for receiving and retaining said attaching members in proper assembled relation when the sail is furled and removed from the spars.

2. A device for detachably connecting sails to spars or the like, comprising slides attached to the sail in spaced relation, a two-part slide guide on the spar, one part of the guide being arranged to receive and retain the slides when assembled, and means for removing said retaining part with the assembled slides.

3. A device for detachably connecting sails to spars or the like, comprising a set of slides attached to the sail in spaced relation, a two-part slide track carried by the spar, one part of said track being detachably connected to the spar, said detachable part being of a length to receive a set of slides when assembled.

4. A device for detachably connecting sails to spars or the like, comprising a set of slides attached to the sail in spaced relation, a two-part slide track carried by the spar, one part of said track being detachably connected to the spar, said detachable part being of a length to receive a set of slides when assembled, and means in said removable part for retaining said slides in proper relation when these parts and the sail are removed from the spars.

5. A device for detachably connecting sails to spars or the like, comprising slides on the

sail, a guide rail on the spar arranged to receive the slides, said rail having a readily removable section arranged to receive and retain the sail slides when assembled.

6. A device for detachably connecting sails to spars or the like, comprising slides on the sail, a guide rail on the spar arranged to receive the slides, said rail having a readily removable section arranged to receive the sail slides when assembled, and means in said removable section for releasably retaining the slide members in proper assembled relation when the sail rail section is removed from the spars.

7. A device for detachably connecting sails to spars or the like, comprising slides on the sail, a guide rail on the spar arranged to receive the slides, said rail having a readily removable section arranged to receive and retain the sail slides when assembled, and means for automatically locking the slides to said removable section when the same is removed from slide receiving position on the spar.

8. A device for detachably connecting sails to spars or the like, comprising slides on the sail, a guide rail on the spar arranged to receive the slides, said rail having a readily removable section arranged to receive and retain the sail slides when assembled, means for automatically locking the slides to said removable section when the same is removed from slide receiving position on the spar, and means for automatically releasing the slides when said section is replaced in working position.

9. A device for attaching sails to spars or the like, comprising slides attached in spaced relation along the margin of the sail, a rail section on the spars to receive the slides, and a magazine removably mounted at the end of the rail in which the slides may be assembled when the sail is furled.

10. A device for detachably connecting sails to spars or the like, comprising slides attached in spaced relation along the margin of the sail, a fixed rail section on the spars on which the slides may run, a rail extension magazine section removably mounted at the end of the fixed section in which the slides may be assembled when the sail is furled, and means in the magazine section for retaining the slides in assembled order when removed with the sail from the spar.

11. A device for detachably connecting sails to spars or the like, comprising slides attached in spaced relation along the margin of the sail, a main rail section on the spar on which the slides may run, a rail extension magazine removably mounted at the end of the rail in which the slides may be assembled when the sail is furled, and means for automatically locking the slides in the magazine when the latter is removed from slide receiving position on the spar.

12. A device for detachably connecting sails to spars or the like, comprising slides attached in spaced relation along the margin of the sail, a rail on the spars to receive the slides, a trough-shaped section removably mounted at the end of the rail providing a magazine in which the slides may be assembled when the sail is furled, means for automatically locking the slides in the magazine when the latter is removed from slide receiving position on the spar, and means for automatically releasing said slides to be withdrawn from the magazine upon replacing the magazine in operating position on the spar. 5
13. A device for detachably connecting sails to spars or the like, comprising a set of slides on the sail, a main track section carried by the spar for removing said slides, and means on the spar for detachably connecting a slide receiving magazine track section to the spar at the end of said main track section. 10
14. A device for detachably connecting sails to spars or the like, comprising a set of slides on the sail, a slide track on the spar, means on the spar for detachably connecting a slide receiving magazine to the spar at the end of the rail, and stop members in the magazine for retaining the slides therein when removed from the spar. 15
15. A device for detachably connecting sails to spars, comprising slides attached in spaced relation along the margin of the sail, a T-shaped rail section on the spars on which the slides may run, and a trough-shaped magazine rail extension section in which the slides may be stored, and means for removably mounting said trough section at the end of the rail in which the slides may be assembled when the sail is furled. 20
16. A device for detachably connecting sails to spars or the like, comprising a set of slides on the sail, a slide track on the spar, means on the spar for detachably connecting a slide receiving magazine to the spar at the end of the rail, stop members in the magazine for retaining the slides therein when removed from the spar, and a cam for automatically withdrawing one of said stops to permit the withdrawal and entrance of the slides when the magazine is positioned on the spar. 25
17. A device for detachably securing sails to spars or the like, comprising a set of slides on the sail, a main slide track on the spar, spaced holding members at one end of the main track, and a short section of slide storing track removably retained in said holding members. 30
18. A device for detachably securing sails to spars or the like, comprising a set of slides on the sail, a slide track on the spars, spaced members at one end of the track, a short section of slide storing track removably retained in said members, stop means at the ends of the removable track section for locking the slides thereon when removed from the mast. 35
19. A device for detachably securing sails to spars or the like, comprising a set of slides on the sail, a slide track on the spars, spaced members at one end of the track, a short section of slide storing track removably retained in said members, stop means at the ends of the removable track section for locking the slides thereon when removed from the mast, and a cam on one of said members arranged to withdraw the stop means to permit the withdrawal of the slides when the magazine is positioned in said members. 40
20. A device for detachably securing sails to spars or the like, comprising a set of slides on the sail, a slide track on the spars, spaced members at one end of the track, a short section of trough-shaped slide storing track removably retained in said members, stop means at the ends of the removable track section for locking the slides therein when removed from the mast, a cam on one of said members arranged to withdraw the stop means to permit the withdrawal of the slides when the magazine is positioned in said members, and a lock in the other of said sections for releasably securing the magazine in operative position. 45
